UNITED STATES PATENT OFFICE

141,685

DESIGN FOR AN ICE AUGER

Richard D. Green, Nashville, Mich.

Application February 19, 1945, Serial No. 118,020

Term of patent 14 years

(Cl. D55—1)

To all whom it may concern:

Be it known that I, Richard D. Green, a citizen of the United States, residing at Nashville, in the county of Barry and State of Michigan, have invented a new, original, and ornamental Design for Ice Augers, of which the following is a specification, reference being had to the accompanying drawing, forming part thereof.

Fig. 1 is a view slightly in perspective of an ice auger showing my new design, and

Fig. 2 is a bottom plan view of the ice auger shown in Fig. 1, illustrating the cutting disc and blades.

I claim:

The ornamental design for an ice auger, as shown.

RICHARD D. GREEN.
